UNITED STATES PATENT OFFICE.

EDWARD L. DELANY, OF BROOKLYN, NEW YORK.

FLUSH-TANK FOR WATER-CLOSETS.

1,320,452.

Specification of Letters Patent.

Patented Nov. 4, 1919.

Application filed December 7, 1917. Serial No. 205,950.

To all whom it may concern:

Be it known that I, EDWARD L. DELANY, a citizen of the United States, residing in the city of New York, borough of Brooklyn, 5 county of Kings, and State of New York, have invented a certain new and useful Flush-Tank for Water-Closets, of which the following is a specification.

This invention relates to flush tanks for 10 water-closets, and, more particularly, to those of the "low-down" type. In tanks of this character, the top or cover is exposed to view and has, in the past, been generally secured to the body of the tank by means 15 of screws passed through the top or cover and threaded into the walls of the tank. This is the general construction in wooden tanks and in some metal ones, although, in the majority of the metal, composition or porcelain 20 tanks, the cover merely rests loosely upon the top of the tank and may be lifted off at will.

In those tanks where the screws project above the top of the tank, they are not only 25 unsightly, but preclude the setting of bottles and other toilet articles upon the tank. In cases where the cover is laid on loosely, there is a tendency of the tenant to lift off the cover, partly through curiosity and frequently in an endeavor to repair the sensitive mechanism incased within the tank. 30 Moreover, it is not unusual for children to tamper with loose covers, and, in instances where the tank is set unusually low, a person 35 sitting too far back on the seat may inadvertently displace the cover.

With the foregoing, and other, disadvantages in mind, the object of the present invention is to so construct the tank that the 40 cover thereof is locked in place thereon by normally invisible or concealed means and in such manner that only such persons as are familiar with its construction can release the cover, through deliberate manipulation 45 of the parts, to allow of the removal thereof for repairs.

From a more specific standpoint, the invention is particularly adapted for composition, cast or porcelain tanks, the cover and 50 side walls of the tank being so formed as to interlock or interfit with one another, concealed means being provided for locking the cover and walls in such interlocked or interfitted relation. Moreover, the results 55 specified are accomplished in a simple, efficient and economical manner.

Features of the invention, other than those adverted to, as well as the advantages thereof, will be apparent from the following detailed description when read in conjunction with the accompanying drawings. 60

In the accompanying drawings I have illustrated one practical embodiment of the invention, but the construction therein shown is to be understood as illustrative, 65 only, and not as defining the limits of the invention.

Figure 1 is a perspective view of the tank, partly in section, showing the preferred manner of locking the top or cover in place. 70

Fig. 2 is a fragmental underneath plan view of a portion of the tank, showing the cover securing means locked in place, and

Fig. 3 is a fragmental elevation of the back of the tank. 75

Referring to the drawings, A designates the body of the tank which is in the form of a receptacle adapted to house the usual float-controlled valve and releasing mechanism, neither of which is shown as it forms 80 no part of the present invention. The tank may be of any shape, form or proportions, and may be suitably ornamented as desired, but is here shown as of simple, rectangular configuration, in the interest of clearness. 85 The tank is provided with a cover B adapted to close the top thereof. Both the tank and cover may be formed from wood, composition, porcelain, or any other material desired. 90

In order that cover B and tank A may be detachably assembled, there is provided, preferably along the front wall of the tank, a rabbet or channel a, which extends along the inner face of the front wall and near 95 the upper edge thereof. With this channel is adapted to coöperate a flange b' formed upon cover B in such manner that, when the cover is in the position shown in Fig. 1, the flange b of the cover will interlock 100 with the channel rabbet a of the tank and lifting of the cover from the tank is precluded, unless said cover is so manipulated as to disengage the interlocked elements.

It will appear that, in order to disengage 105 the interlocked elements, it will be necessary to tilt up the back edge of the cover, and, as long as the cover is held down against such tilting movement, the parts will be maintained in interlocked relation. Means 110 is provided for locking the cover against the pivotal or tilting movement referred to,

and this means is preferably in the form of one or more anchor rods C, one of which is here shown in the interest of clearness. Anchor rod C extends vertically up the back 5 of the tank and exteriorly thereof, the rod being positioned in a vertical channel a' formed in the back wall of the tank, so that the rod will be set in from the plane of the back of the tank and will not interfere with 10 the positioning of the tank tight against a wall. Rod C is provided with a hook-shaped portion c at its upper end, which hook-shaped portion is adapted to project into a pocket d formed in cover B, and, 15 through the coöperation of the hook and pocket, rod C is secured to the cover in a manner which will be apparent. The lower end of rod C projects beneath the bottom of the tank and is provided with a slot e, with 20 which is adapted to coöperate a wedge E operating against a washer plate F which bridges channel a' and through which rod C is passed, said construction being best shown in Fig. 3.

25 The assembling of the parts and their mode of operation will be apparent, it being manifest that, after flange b' is interlocked with channel a' , anchor rod C is clamped down tight by forcing in the wedge E. This 30 operation may be accomplished either before the installation of the tank or thereafter, since the channel a' in the back of the tank allows of sufficient clearance for the ready insertion of the rod.

35 Low-down tanks of the character described are invariably placed with their backs tight against a wall, and this fact makes it impossible to shift the cover rearwardly to allow of the disengagement of 40 flange b' from channel a' , as the back edge of the cover or top B will rest against the wall of the building. However, the releasing of the flange will be rendered absolutely impossible until rod C is released. Anchor 45 rod C will hold the cover down in tight frictional engagement with the end walls of the tank, so that the structure will be rigid and no rattling can occur. When it is desired to remove the cover, it is only necessary to 50 drive out wedge E, whereupon rod C is released and the cover may be removed. In order that the joint between the cover and the upper edge of the tank may be concealed, the sides and front edge of the cover 55 are preferably provided with a depending flange b'.

In the preferred embodiment of the invention shown, the interlocking portions of the cover and tank are shown as extending 60 from one end of the tank to the other, but, in practice, flange b may be in the form of one or more fingers which coöperate with a like number of sockets α in the wall of the tank. The invention, broadly, contemplates 65 interlocking or interfitting coöperating parts

on the tank and cover, and thereafter locking such parts against disengagement from one another, whereby the cover is precluded from disengagement from the tank.

In adapting the invention to different 70 forms of tanks, the construction of the interlocking parts, as well as the means for locking these parts against disengagement from one another, may be varied in accordance with the environment in which they 75 are employed, and it is, therefore, to be understood that the present invention is not limited to the specific details of construction hereinbefore described, but that the same is as broadly novel as is commensurate 80 with the appended claims.

Having thus fully described the invention, what I claim as new, and desire to secure by Letters Patent, is:

1. A flush tank for water-closets embodying a tank, a cover therefor, interlocking flanges on the tank and the cover, adapted to be moved into and out of interlocking relation by pivotal movement of the cover, and means for locking the cover against 90 pivotal movement when in a position to seal the tank.

2. A structure of the class described embodying a tank, a cover therefor, a member at the top edge of the front wall of the tank 95 adapted to interfit with a coöperating member near the front edge of the cover, and means concealed rearwardly of the back wall of the tank for locking the cover in place.

3. A structure of the class described embodying a tank provided at its top with an interlocking member, a cover provided with an interlocking member adapted to coöperate with the interlocking member on the 105 tank, means secured to the back portion of the cover and extending downwardly at the back of the tank, and a device for securing said means to the body of the tank, whereby the cover is locked in place.

4. A flush tank for water-closets embodying a tank, a cover therefor, interlocking flanges on the tank and the cover, adapted to be moved into and out of interlocking relation by pivotal movement of the cover, 115 and normally concealed means for locking the cover against pivotal movement when in a position to seal the tank.

5. A structure of the class described embodying a tank, a cover therefor, a locking 120 member having a portion seated within the cover of the tank, and means, coöoperating with said member and the bottom of the tank for tightly clamping the cover in place.

6. A structure of the class described embodying a tank, one of the walls of which is provided on its outer surface with a substantially narrow groove, a cover for the tank provided with a concealed socket 130

in proximity to the top of said groove, and a locking member traversing the groove, one end of which fits into said socket and the other end of which is provided with 5 means for securing the locking member in fixed relation to the tank.

7. A structure of the class described embodying a tank, one of the walls of which is provided on its outer surface with a substantially narrow groove, and one of the walls of which is provided near its upper edge with an offset, a cover for the tank provided with a concealed socket in proximity to the top of said groove and at one 10 of its edges an off-set coöoperating with the off-set on the wall of the tank, and a locking member traversing the groove, one end of which takes into said socket and the other end of which is provided with means 15 for securing the locking member in fixed relation to the tank.

8. A structure of the class described embodying a tank, the top front end of which is provided with a flange, a cover for the 20 tank having an interfitting flange coöperating with said flange on the tank, and a

rod extending vertically of the tank and having a hook at its upper end fitting into a depression in the cover of the tank, the other end of said rod extending below the 30 tank and being provided with a slot and wedge, whereby the rod may be tightened and the cover locked against inadvertent disengagement.

9. A structure of the class described embodying a tank, the top front end of which is provided with a flange, a vertically extending groove in the outer face of the back wall of said tank, a cover for the tank having an inter-fitting flange coöoperating with 40 said flange on the tank, and a rod traversing the specified groove and having a hook at its upper end fitting into a depression in the cover of the tank, the other end of said rod extending below the tank and being 45 provided with a slot and wedge, whereby the rod may be tightened and the cover locked against inadvertent disengagement.

In testimony whereof I have signed my name to this specification.

EDWARD L. DELANY.
